UNITED STATES PATENT OFFICE.

ADOLPHUS DAVIS, OF MONTREAL, QUEBEC, CANADA.

SLEEPING-CAR.

SPECIFICATION forming part of Letters Patent No. 240,671, dated April 26, 1881.

Application filed January 14, 1881. (No model.)

To all whom it may concern:

Be it known that I, ADOLPHUS DAVIS, of the city of Montreal, in the district of Montreal and Province of Quebec, Canada, have invented 5 certain new and useful Improved Fittings for Combined Sleeping and Drawing-Room Cars; and I do hereby declare that the following is a full, clear, and exact description of the same.

10 My invention is specially applicable to the cars for which Letters Patent No. 181,857 were granted to Gustave Leve, in which vertical cupboards swing out to carry the berth-frames, or are shut in against and form part of the 15 sides of the cars; and it consists in an improved construction of the cupboard-frames, their supports, and the means by which they are held in place, the supports for the berths, and also for the chairs, which are used when 20 the car is converted into a drawing-room car.

For full comprehension of the invention reference must be had to the accompanying drawings, forming part of this specification, in which—

25 Figure 1 is a horizontal section of one of the cupboards or frames; Fig. 2, a part inside view; Fig. 3, a part of a cupboard-front, and Fig. 4 a view showing berths in place. Fig. 5 shows details of brackets carrying cupboards 30 and means for securing same in place; Fig. 6, details of outside brackets, and Fig. 7 those on the inside for carrying the berth-frames. Fig. 8 is a sectional elevation of chair-support; Fig. 9, a plan view of socket of same; Fig. 10, an end view, and Fig. 11 a plan of chair-seat.

35 Similar letters of reference indicate like parts.

A is the cupboard-front, the lower part being preferably formed of a light casting perforated 40 as at a, A' A' being the cupboard-sides, carried on the brackets B B, which are usually of the same height as the lower part of the cupboard-front. By this arrangement the heat from the steam-pipes is diffused equally from 45 the sides all over the car. In these brackets are formed bearings for wheels b, on which the whole cupboard runs.

C are the hinges by which these cupboards are secured to the walls of the cars, and, as 50 shown in Figs. 1 and 2, clipping the end of a

band of metal, D, passing right round the inside at the level of the berth-frames.

E are the berth-supports on the outside of the cupboard, and F those on the inside, (shown respectively in Figs. 6 and 7,) these being secured to or made in one with plates E' and F', bolted to each other through A; and e and f are the pins upon which the berth-frames, suitably arranged for the purpose, rest. In addition to this, the support E has a hook, E², for 60 hats, &c., formed on its lower side, and on its upper preferably a ring, E³, through which passes a rod, E⁴, as shown in Figs. 3 and 6. The combined hook and berth-support just described will be found very convenient, as it affords means for hanging up clothes, not only when the car is arranged as a parlor-car, but for the occupant of each berth when the beds are made up for the night and within the berth itself. 65

G G are the bolts which secure in place the cupboards A A either when swung out to carry the berths or when turned in against the sides of the car. These slide up and down in sleeves H, secured to brackets B, and in which are 70 formed two openings, h h', to receive the locking end G² of a bent lever, G', pivoted, as shown, to G in a slot, g, formed therein.

To raise the bolt from the position shown in Fig. 5 (viz., from the socket I, formed in the 80 floor of the car) all that is needed is, first, to cant the handle G' upward, so as to release the locking end G² from the slot h, and then to raise the bolt till the end G² comes opposite to and falls in the opening h', thus in either position 85 locking the bolt firmly in place and preventing shaking or rattling.

The construction of the chair-supports may be thus described.

K is a deep rabbeted socket secured to the 90 floor of the car, (any number of these being placed where desired,) either countersunk so as to be flush with the surface or otherwise arranged so as to give no inconvenience. Its lower part is preferably, as shown at K', formed 95 with a thread, in which works the screwed end l of a spindle, L, with handle L' and shoulder L² formed on it.

N is an inner socket resting, when in place, on the shoulder K² of the socket K, and with 100

its flange N' just clear of the upper surface, so as to prevent friction. To this is secured, in any usual and suitable way, the spring-support O, (shown in Fig. 8,) perforated, as shown at O', to allow the spindle to pass through it, and having secured to its upper end the frame P, on which is slipped the framing Q of a chair-seat of some such construction as that shown, and secured in place by a spring or other suitable device.

In many cases the screw-thread l, cut on the end of the spindle L, and corresponding thread, K', in the socket K, may be omitted, the spindle simply dropped into place holding the chair 15 with sufficient security and being more easily removed.

By this arrangement and construction of chair-supports a combined revolving and rocking chair is produced, (the chair proper is also 20 capable of being adapted for a reclining position,) the spring O and socket N revolving freely in the socket K and being securely held in place by the spindle L, by the removal of which the chair and support can be at once detached 25 from the floor, the former being stowed away in any convenient compartment for the purpose, or underneath the berths, and the supports and spindles detached and secured to the cupboards A under the bed-frames, as shown in Fig. 2.

Having thus described my invention, I beg 30 to state that what I claim is as follows:

1. The combination, with the cupboards A, constructed as described, of the brackets B, sleeve H, and bolt G, substantially as and for the purposes set forth. 35

2. The device E, as made with a plate, E', clothes-hook E², and berth-holding pin e, arranged on the cupboard A so that while supporting the berth it shall be inside the same, as and for the purposes set forth. 40

3. The combination, with the swinging cupboards A, of the bolt G, working in sleeve H, raised and lowered and locked in either position in the same by means of handle G', all substantially as herein set forth, and for the 45 purposes described.

4. In a drawing-room-car chair, a revolving 50 rocking support consisting of a curved spring carrying on its upper end a frame, and bolted at its lower end to an eye or socket resting in a seat formed in the floor and secured therein by a loose pin or spindle, all substantially as herein described, and for the purposes set forth.

ADOLPHUS DAVIS.
